UNITED STATES PATENT OFFICE.

JOHN WILLIAM ENDEAN, OF DEVONPORT, ENGLAND.

SAND-BOX AND MECHANISM FOR ACTUATING SAME.

SPECIFICATION forming part of Letters Patent No. 728,094, dated May 12, 1903.

Application filed August 29, 1902. Serial No. 121,501. (No model.)

To all whom it may concern:

Be it known that I, JOHN WILLIAM ENDEAN, a subject of the King of England, residing at 25 Alexandra road, Ford, Devonport, in the county of Devon, England, have invented certain new and useful Improvements in Sand-Boxes and Mechanism for Actuating the Same; and I do hereby declare the following to be a full, clear, and exact description of the invention, such as will enable others skilled in the art to which it appertains to make and use the same.

In constructing a sand-box according to my invention I employ two castings for each pair of wheels, each tapering to a nozzle end, to which is attached an india-rubber or other pipe to convey the sand to the rails. These castings are bolted to the floor of the tram-car or other vehicle in a position suitable to the gage of the rails. Holes corresponding to the size of the sand-box are cut in the floor, over which hoppers are fixed in such a position as to get a direct fall for the sand. The inside face of the casting is removable and attached to the main casting by bolts or otherwise in order to form a detachable door. The interior of the casting is formed so as to admit an oscillating tumbler with a square hole, and when sand is required this hole is brought to an upright position by suitable mechanism and when shut off assumes a horizontal position, thus preventing the sand from running to waste. The tumbler works on a spindle, one end of which projects through the main casting and the other through the detachable door above mentioned. To the portion of the spindle on the outside of the casting a pin is attached which works in a boss on the casting formed to allow the tumbler to open fully and close. To the spindle working through the door is attached a crank fixed to a bar carrying a similar crank at its other end, this latter crank being fitted to a cross-bar spaced to the same gage as the boxes. Near the center of the platform, where the car-driver stands, a loose pin passes through the floor and lies in a hole in a crank attached to the center of the cross-bar before mentioned. The cranks fixed to the spindles in

the boxes are held in position by strong spiral springs fastened to the framework of the car, so that the sand is shut off or turned on

by the driver pressing with his foot on the loose pin. All the cranks and rods move simultaneously and allow the tumblers to oscillate, so that the openings become a quarter, a half, or fully open, as required. This action stretches the springs, and when the driver's foot is taken off the pin the springs contract and bring the cranks back to their normal position, shutting off the sand. Each sand-box may be made to work independently of the other, if this is required, by disconnecting the crank which controls that box which it is not desired to use.

In order that my said invention may be better understood, I will now proceed to describe the same with reference to the drawings accompanying this specification, in which—

Figure 1 shows plan of sand-box; Fig. 2, elevation of inside face; Fig. 3, end view; Figs. 4, 5, and 6, details of tumbler; Figs. 7 and 8, cover detached; Fig. 9, details hereinafter referred to; Fig. 10, plan showing general arrangement; Fig. 11, section at A B, Fig. 10; Fig. 12, section at C D, Fig. 10. Figs. 10, 11, and 12 are drawn to a smaller scale than the other figures.

The same letters of reference are employed to denote the same parts in all the views.

a shows main casting with nozzle end *b*. This casting is bolted to the floor of the car, as shown at Fig. 11. Holes corresponding to the size of the sand-box are cut in the floor. Over the casting *a* a hopper *c* is fixed.

d shows a detachable door or face attached to the main casting.

e is an oscillating tumbler mounted on the casting *a*, as shown. This tumbler *e* is formed with a square hole *f* and may be turned to allow sand to pass, as in the position shown at Fig. 3, or may be turned to block the passage of sand or to any desired intermediate position. The tumbler *e* works on the spindle *g*, one end of which projects through the main casting and the other through the detachable door *d*.

h shows pin attached to the spindle *g*. This pin *h* works in a boss *i*, which is formed to allow the tumbler *e* to open fully and close, as shown at Fig. 9.

j shows a crank attached to the spindle *g* and bolted to a bar *k*, having a similar crank *m* attached to the other end. This latter crank

m is fitted to a bar *n*, spaced to the same gage as the boxes.

o shows a loose pin passing through the floor near the center of the platform and resting under the recess in one end of the crank *p*, fixed on the cross-bar *n*.

q shows spiral spring fastened to the framework of the car and by means of a chain to the crank *j*.

10 10 The driver by actuating with his foot the loose pin *o* turns the tumbler *e*, so that the sand is turned on or off, as required. The tumbler *e* may in the same manner be turned partially instead of completely.

15 15 *r r*, Fig. 2, show two pieces of rubber or other material placed in slots the full width of the tumbler, so as to prevent leakage from between the tumbler and the main casting.

20 20 What I claim, and desire to secure by Letters Patent of the United States of America, is—

25 25 1. In a sanding-box, the combination with a main casting, provided with a hollow chamber therethrough, a hopper above said chamber, a detachable door forming one side of said casting and chamber, an oscillating tumbler mounted in said chamber, journaled to one of the side walls thereof and said detachable door, and provided with an aperture 30 30 therethrough adapted to communicate with the delivery end of said hopper, and means for oscillating said tumbler.

35 35 2. In a sanding-box, the combination with a main casting, provided with a hollow chamber therethrough, a hopper above said chamber, an oscillating tumbler, having an aperture therethrough and provided with spindles journaled in said casting, means for oscillating said tumbler, a boss on said casting, and a pin on one of said spindles engaging said boss for limiting the oscillation of said tumbler.

40 40 3. In a sanding-box, the combination with a main casting, provided with a hollow chamber therethrough, a detachable door, a delivery-nozzle located below said chamber, a hopper above said chamber, an oscillating tumbler, mounted in said chamber, having an aperture therethrough, adapted to communicate with the delivery end of said hopper and said 45 45 delivery - nozzle, means for oscillating said tumbler, a boss on said casting, a pin carried by said tumbler, adapted to engage said boss for limiting the oscillation of said tumbler, and rubber bushings extending longitudinally of said tumbler for preventing leakage between the tumbler and said casting.

50 50 In testimony whereof I affix my signature in presence of two witnesses.

JOHN WILLIAM ENDEAN.
